UNITED STATES PATENT OFFICE.

FREDERICK A. CLEVELAND, OF NEW YORK, N. Y.

BINDER.

No. 829,326.

Specification of Letters Patent.

Patented Aug. 21, 1906.

Application filed February 15, 1906. Serial No. 301,253.

To all whom it may concern:

Be it known that I, FREDERICK A. CLEVELAND, a citizen of the United States, and a resident of the city of New York, in the county of New York and State of New York, have invented certain new and useful Improvements in Binders, of which the following is a specification.

This invention relates to binders of the loose-leaf type, the object being to provide a device of simple construction for use in connection with covers or binders of this class which will be positive in its action and easily operated. The use of binders of this description is well understood, and it is not thought necessary to enter into an explanation of their operation further than to state the principal requirement, which is that any number of pages or leaves may be inserted, replaced, or taken out without disturbing the remaining leaves.

The object of my invention is to provide a device which shall meet this requirement and accomplish the result by the use of a simple locking mechanism which does not require separate keys or other devices to operate the same and which shall be self-contained and operated by turning the book on one side to lock the covers in any desired position and to release the same by simply reversing the position of the book. To accomplish this result, I provide an upper and lower clamping-section, which may be attached to the covers of a binder. These clamping-sections are normally held apart by the action of springs contained in telescoping members attached to said clamping-sections in the usual manner. Attached to one of these clamping-sections, preferably the upper, I provide a post which carries a pawl or dog which is adapted to engage projections on the interior of a cooperating post or casting which is secured to the lower clamping-section. This latter post or casting is adapted to telescope over the post carrying the pawl or dog. The construction of these parts is such that when the clamping-sections are in the position just indicated a free inward movement is permitted, and the pawl or dog will operate to prevent an outward movement of the members. As the position of the clamping-sections and attached covers is reversed the pawl or dog will fall out of engagement and allow the clamping-sections to be separated by the ac-

tions of the springs heretofore referred to or 55 by other suitable means.

The construction and operation of the device will be more fully explained in connection with the drawings accompanying this specification. 60

Figure 1 is a perspective side elevation of a pair of clamping-sections or binder-frames with the covers and leaves of the book omitted. Fig. 2 is an enlarged side elevation in section of the telescoping members carrying 65 the locking mechanism. Fig. 3 is an enlarged side elevation and detail view of the post carrying the pawl or dog.

In Fig. 1 at 1 and 2 are shown an upper and lower clamping-section, respectively, which 70 may be attached by any suitable means to the covers of the binder. At 3 are shown telescoping members containing springs which operate normally to separate the clamping-sections 1 and 2. At 4 is shown a 75 post attached to the upper clamping-section 1 by any suitable means and preferably in such a manner that it may be rotated therein. This post carries at its lower end a pawl or dog, such as shown at 5. This pawl is pivotally attached to the post 4 in a slot at the lower end thereof and may swing freely to either side and engage the serrations or projections on the inside of the casing 7 when the parts are in the position shown in the 85 drawings.

In Fig. 2 the pawl is shown in its operative position engaging one of the telescoping members. The serrations or projections on the interior of the casing 7 are preferably in 90 the form of a spiral or thread in order to provide for a final tightening of the clamping members by turning the post 4. A slot may be provided at the lower end of the post 4, in which is positioned the pawl 5 and a recess 95 connecting therewith, in which one or more auxiliary weights, preferably spherical in shape, such as 8, are contained. The object of these weights is to insure a more positive action and a quicker movement of the pawl 100 or dog 5. This allows the pawl or dog to be made very small and light, thus taking up very little space and permitting of a very compact construction, which is especially desirable in a device of this kind, at the same time 105 by the use of these auxiliary weights, which are contained in the post itself, and so require no additional room, all of the advantages of a

heavier dog are obtained and in addition a much quicker action is insured because of the fact that when the covers and clamping-sections are reversed in position from that shown in the drawings these weights will quickly fall away from the dog and allow it to drop out of engagement with the casing and permit the post 4 to be drawn out until the shoulder provided on the same engages the outer end of the casing 7.

The pawl or dog 5 is of peculiar construction and embodies some of the principal features of my invention. In its preferred form (illustrated in the drawings) the pawl is pivotally attached to the lower end of the post 4 in the slot provided therefor, as above described. Projections are provided intermediary of the ends of the pawl, said projections being located on opposite sides thereof and are adapted to engage the serrations on the interior of the casing 7 on either side, depending upon which way the pawl falls. At the end opposite to the pivot a tapered projection is provided, which is adapted to be engaged by the auxiliary weights 8. The object of these weights, as has been stated, is to insure a more positive and quicker movement of the pawl, and, furthermore, when the parts are in the operative position, as shown in Fig. 2, these weights assist in holding the pawl in engagement with the casing on account of the wedging action of the same between the retaining-wall of the recess and the tapered projection on the pawl.

While in the preferred construction shown two engaging projections or points are provided on opposite sides of the pawl, it will be evident that the same would be operative with one such projection. In this case it would only be necessary to provide a stop to limit the movement and insure the falling of the pawl to one side to lock the telescoping members against the separation.

In operation, assuming that the covers stand in the position shown in the drawings, any desired number of leaves may be inserted between the clamping-sections and covers and the upper cover may be pressed down until the leaves are securely clamped or held and the cover will be retained in such a position by means of the locking dog or pawl, as explained. A further tightening may be effected by turning the post 4 and the attached dog, which engages the spiral thread-like projections on the interior of the casing 7. The post 4 may be turned by using an ordinary screw-driver in the slot of the screw at the upper end thereof or by other suitable means.

It will be seen from the foregoing description that all of the moving parts are contained within the inner post and that no springs or other actuating means are necessary to insure the positive operation of the

locking pawl or dog, gravity alone being the actuating force.

As many changes could be made in the above construction and many apparently widely different embodiments of my invention could be made without departing from the scope thereof, I intend that all the matter contained in the above description or shown in the accompanying drawings shall be interpreted as illustrative and not in a limiting sense.

What I claim is—

1. In a binder-lock, in combination, a pair of telescoping members, and a pawl or dog carried by one of the said members having engaging projections located intermediary of the ends and on opposite sides of the axis thereof and adapted to engage the other of said members.

2. In a binder-lock, in combination, a pair of telescoping members, a pawl or dog carried by one of said members having engaging projections on opposite sides thereof and adapted to engage the other of said members, and an auxiliary weight coöperating with said pawl or dog to accelerate the action of the same.

3. In a binder-lock, in combination, a pair of telescoping members, a pawl or dog carried by one of said members having engaging projections located on opposite sides and intermediary of the ends thereof and adapted to engage the other of said members, and an auxiliary weight coöperating with said pawl or dog to accelerate the action of the same.

4. In a binder-lock, in combination, a pair of telescoping members, a pawl or dog having one end pivotally attached to one of said members and the opposite end thereof adapted to be engaged by an auxiliary weight and also having a portion thereof adapted to engage the other of said members, and an auxiliary weight adapted to engage said pawl or dog to accelerate the action of the same.

5. In a binder-lock, in combination, a pair of telescoping members, a pawl or dog having one end pivotally attached to one of said members and the opposite end thereof adapted to be engaged by an auxiliary weight and also having a portion located intermediary of the ends thereof adapted to engage the other of said members, and an auxiliary weight adapted to engage said pawl or dog to accelerate the action of the same.

6. In a binder-lock, in combination, a pair of telescoping members, a pawl or dog having engaging projections on opposite sides intermediary of the ends thereof and also having a projection at one end adapted to be engaged by an auxiliary weight, and an auxiliary weight coöperating with said pawl or dog to accelerate the action of the same.

7. In a binder-lock, in combination, a pair of telescoping members, an oscillatory pawl

or dog carried by one of said members and having engaging projections on opposite sides intermediary of the ends thereof adapted to engage the other of said members, and 5 an auxiliary weight coöperating with said pawl or dog to accelerate the action of the same.

8. In a binder-lock, in combination, a pair of telescoping members, an oscillatory pawl 10 or dog pivotally attached to one of said members and having engaging projections on opposite sides intermediary of the ends thereof adapted to engage the other of said members, and an auxiliary weight coöperating with 15 said pawl or dog to accelerate the action of the same.

9. In a binder-lock, in combination, a pair of telescoping members, a pawl or dog pivotally attached to one of said members and having 20 a projection adapted to be engaged by an auxiliary weight and also having portions on opposite sides thereof adapted to engage the other of said members, and an auxiliary weight coöperating with said pawl or dog to 25 accelerate the action of the same.

10. In a binder-lock, in combination, a

pair of telescoping members, a pawl or dog having one end pivotally attached to one of said members, said pawl or dog having a portion thereof adapted to be engaged by an auxiliary weight and also having portions on opposite sides thereof adapted to engage the other of said members, and an auxiliary weight adapted to engage said pawl or dog to 30 accelerate the action of the same. 35

11. In a binder-lock, in combination, a pair of telescoping members, a pawl or dog having one end pivotally attached to one of said members and the opposite end adapted to be engaged by an auxiliary weight and 40 also having portions on opposite sides thereof adapted to engage the other of said members, and an auxiliary weight adapted to engage said pawl or dog to accelerate the action of the same. 45

Signed at New York city, in the county of New York and State of New York, this 24th day of January, A. D. 1906.

FREDERICK A. CLEVELAND.
